TRANSISTOR ELECTRODE SUPPORT ELEMENT

Raymond J. Andres, Newport Beach, and Peter V. N. Heller, Dana Point, Calif., assignors to Hughes Aircraft Company, Culver City, Calif., a corporation of Delaware

Filed June 22, 1961, Ser. No. 65,680

Term of patent 14 years

(Cl. D26—5)

FIG. 2.

FIG. 1.

FIG. 3.

FIG. 1 is a front elevational view of a transistor electrode support element, showing our new design;

FIG. 2 is a side elevational view, partly in cross-section taken on line 2—2 of FIG. 1; and

FIG. 3 is a bottom plan view thereof, partly in cross-section taken on line 3—3 in FIG. 1.

We claim:

The ornamental design for a transistor electrode support element, as shown and described.
